FEEDING AND EJECTING DEVICE FOR
CENTERLESS GRINDERS

John E. Heckethorn, Denver, Colo.

Application July 7, 1945, Serial No. 603,658

3 Claims. (Cl. 51—103)

1

This invention relates to an automatic infed and ejecting attachment for centerless grinding machines and is designed more particularly as an improvement over the invention illustrated in copending application Serial No. 497,102, now Patent Number 2,379,961.

The principal object of this invention is to provide a simple and highly efficient pneumatically-operated mechanism for automatically placing work pieces in a centerless grinding machine and removing the finished pieces therefrom.

Another object of the invention is to so construct the device that it will operate synchronously with the advance and withdrawal of the feed wheel of a conventional centerless grinding machine.

A still further object is to provide a device of this character which will be economical to manufacture, rugged in structure and positive in operation.

Other objects and advantages reside in the detail construction of the invention, which is designed for simplicity, economy, and efficiency. These will become more apparent from the following description.

In the following detailed description of the invention reference is had to the accompanying drawings which forms a part hereof. Like numerals refer to like parts in all views of the drawings and throughout the description.

In the drawings:

Fig. 1 is a side view of a typical centerless grinding machine, illustrating the elements of the invention in place thereon;

Fig. 2 is an enlarged, longitudinal section through the work ejecting mechanism employed in the improved attachment;

Fig. 3 is a detail, cross-section, taken on the line 3—3, Fig. 6;

Fig. 4 is a similar cross-section taken on the line 4—4, Fig. 2;

Fig. 5 is a similar cross-section taken on the line 5—5, Fig. 6;

Fig. 6 is an enlarged cross-section through the grinding machine illustrating the attachment in place thereon; taken on the line 6—6, Fig. 1;

Fig. 7 is a detail view illustrating a valve operating cam employed in the attachment;

Fig. 8 is a detail view illustrating a face view of the valve operated by the cam of Fig. 1;

Fig. 9 is a side view of the valve of Fig. 8; and

Fig. 10 is a cross-section through the valve of Fig. 9.

Standard parts of a typical centerless grinding machine are designated on the drawings by

2

numeral as follows: bed 10, grinding wheel 11, feed wheel 12, feed wheel motor housing 13, feed wheel carriage 14, feed wheel carriage feed screw 15, feed wheel feed sleeve 16, hand wheel 17, grinding wheel motor 18, grinding wheel housing 19, work rest 20, work rest holder 21, lower slide 22, ejection plunger 23, and work pieces 54.

In such a machine the work being ground rests upon the work rest 20 between the grinding wheel 11 and the feed wheel 12. The feed screw 15 is rotated by means of the hand wheel 17, to bring the feed wheel carriage 14 adjacent the work. The feed sleeve 16 is then rotated on the feed screw to move the carriage 14 forwardly for a present distance sufficient to bring the work to the required finished diameter. Therefor the amount of rotation of the feed sleeve 16 determines the amount of grinding which will be done and the sleeve must be circumferentially reciprocated a preset distance for each article to be ground. The wear of the grinding wheel is adjusted during operation by rotation of the hand wheel 17.

This invention is designed to automatically place the work pieces 54 between the wheels 11 and 12; rotate the feed sleeve 16 at the proper speed and for the proper distance to bring the workpiece to the acquired finished diameter; then withdraw the feed wheel 12 by return reciprocation of the feed sleeve 16; and eject the finished work piece from between the wheels 11 and 12. With the exception of the grinding wheel 11, only the parts added to the standard centerless grinder are shown shaded in the drawings. The unshaded parts will be found in all standard machines.

The mechanism for reciprocating the feed sleeve 16 is shown and described in detail in the said copending application, Serial No. 497,102. In this invention the same mechanism is used and will be briefly described herein as follows:

A base plate 24 is mounted on the motor housing 13 and carries an operating motor 25 which, through the medium of a V-belt 26 and a speed reducer 27, rotates a cam shaft 28. The shaft 28 projects from both faces of the speed reducer and on the front face terminates in a large cam member 29 provided with a face cam track. A rocker arm 30 is journaled in suitable bearings on the plate 23 and projects both above and below the latter. The upper extremity of the rocker arm terminates in a cam follower 31 which follows the face cam in the member 29 to impart a reciprocating movement to the rocker arm 30. The lower part of the rocker arm 30 is connected to a crank member 32 on the feed sleeve 16. Thus, at each

rotation of the cam member 29, the feed sleeve 16 will be rotated forward and back to move the feed wheel 12 toward the work piece and away therefrom.

The present invention makes use of the cam shaft 28 for timing its operation so that the in-feed and ejection of the work pieces will be in synchronism with the movements of the rocker arm 30.

The present invention employs a valve cam 33 mounted on the cam shaft 28. A two-way valve housing 34 is mounted in a valve bracket 35 secured to the base plate 24 opposite and below the cam 33. The valve housing contains a valve plug 36 having a stem 37 projecting from the housing 34. The stem terminates in a valve operating lever 38 carrying a roller 39 in the path of the cam 33. Thus, as the cam rotates in a counter-clockwise direction in Fig. 7, it will contact the roller 39 causing the lever 38 to rotate the valve plug 36 90°. When the cam 33 leaves the roller 39 a spring 40 will return the lever 38 to its former position.

Compressed air from any suitable source is supplied to the valve housing 34 through a compressed air pipe 41 and flows from and to the housing through a feed pipe 42 and a return pipe 43, respectively. The housing is also provided with exhaust ports 44. The valve is a conventional two-way type, that is, when the plug is rotated in one direction it will connect the feed pipe 42 with the compressed air pipe 41 and the return pipe 43 to one of the exhaust ports 44. When the plug is rotated in the other direction it will connect the return pipe 43 with the compressed air pipe 41 and the feed pipe 42 with one of the exhaust ports 44. The feed pipe 42 is connected with the outer extremities of an infeed cylinder 45 and an ejection cylinder 46 through the medium of flexible hoses 47, and the return pipe 43 is connected with the inner extremity of these two cylinders by means of similar hoses 48.

The infeed cylinder 45 is supported in an inverted channel arm 49 which in turn is supported from the work rest holder 21 in a suitable bracket 50. The bracket 50 also supports a slide track bar 51 (see Fig. 5), along which, a pusher block 52 travels, and a work piece magazine 53 containing a vertical pile of unfinished work pieces 54. The pusher block is designed to push the lowermost work piece 54 from the pile inwardly along a projecting floor member 55 until it falls by gravity to the work rest 20.

The cylinders 45 and 46 are standard actuating cylinders which may be purchased on the open market and contain a suitable piston (not shown) for actuating a projecting piston rod 56.

The piston rod 56 of the infeed cylinder 46 is connected to the pusher block 52 to reciprocate the latter inwardly and outwardly. An adjusting screw 57 is connected to the outer extremity of the cylinder 46 by means of which the position of the cylinder 46 may be adjusted to properly position the pusher block 52.

The ejection cylinder 46 is mounted in a second inverted channel arm 58 which is supported from a hollow bracket casting 59 attached to the side of the work rest holder 21. An ejector rod 60 extends longitudinally of the arm 58 and the casting 59 and terminates in an ejection head 61 positioned to force the completed workpiece 54 from the work rest onto a receiving chute 62 which carries it from the machine.

The piston rod 56 of the cylinder 46 is adjustably connected to the ejector rod 60 through the

medium of a toggle member 63 so that each reciprocation of the piston rod of the cylinder 46 will be communicated to the ejector head 61 to force the finished work piece from the work rest. The cylinder 46 is also adjustably supported from an adjusting screw 64 by means of which the position of the entire assembly may be adjusted.

A rocking yoke 65 is mounted on a pivot pin 66 in the hollow bracket 59. One extremity of the yoke 65 is positioned opposite the ejection plunger 23 of the grinding machine. The other extremity thereof is forked to receive the ejector rod 60 so as to act against a set collar 67 thereon. This enables the operator to use the conventional ejector mechanism when desired, without interference with the automatic ejector mechanism.

It is believed that the operation of the device can be understood from the above. Briefly, the magazine 53 is filled with rough work pieces such as artillery shells, and the motors driving the grinding and feed wheels 11 and 12 and the operating motor 25 are started. Let us now assume that one of the work-pieces is resting on the work rest 20. The rotation of the cam 29 will act on the feed sleeve 16 to bring the feed wheel 12 against the work-piece so that the desired amount of material will be removed by the grinding wheel 11.

The cam 29 will now reverse the sleeve to withdraw the feed wheel 12 and simultaneously the cam 33 will contact the roller 39 so as to rotate the valve plug 36 to admit air under pressure from the pipe 41 to the outer extremities of the two cylinders 45 and 46. It will also simultaneously connect the inner extremities of these cylinders with the exhaust ports 44.

This causes the ejector head to force the finished work-piece from the rest 20 and also causes the pusher block to force the lowermost rough work-piece from the pile in the magazine 53 to a position between the wheels 11 and 12. The ejector head 61 temporarily supports the latter work piece and the pusher block 52 temporarily supports the pile of rough work pieces in the magazine 53.

The cam 33 now releases the roller 39 allowing the spring 40 to return the valve plug 36 to its former position so as to connect the inner extremities of the cylinders 45 and 46 with the compressed air pipe 41 and the outer extremities with the exhaust ports 44 so that both the pusher block 52 and the ejector head will be snapped outwardly. The cam 29 now brings the feed wheel 12 against the newly inserted work-piece.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A work-piece feeding and ejecting attachment for centerless grinding machines, of the type having a grinding wheel, a feed wheel and a work rest positioned between said wheels, comprising: a horizontal in-feed guide member extending into the space between said wheels above said work rest; a magazine supporting a vertical pile of work-pieces on said guide member; a pusher block positioned to push the lowermost work-piece from said pile and from said guide member so that it may fall by gravity to said work rest; a pneumatic cylinder; a piston in said cylinder; a piston rod extending from said piston to

an operative connection with said pusher block to actuate the latter; a two-way valve for alternately connecting the opposite ends of said cylinder with a source of fluid pressure; a motor operated device for moving said feed wheel toward and away from said grinding wheel; means for operating said valve from said latter device so that the movements of said valve will be in synchronism with the movements of said feed wheel; an ejector rod positioned on the opposite side of the work rest from said pusher block in alignment with a work-piece resting on said rest; a second pneumatic cylinder; a second piston; a second piston rod connecting said second piston with said ejector rod for actuating the latter; and pneumatic conduits connecting said second cylinder with said valve so that the latter will control the ejection of the finished work pieces from said work rest.

2. A work-piece feeding and ejecting attachment for centerless grinding machines, of the type having a grinding wheel, a feed wheel and a work rest positioned between said wheels, comprising: a horizontal in-feed guide member extending into the space between said wheels above said work rest; a magazine supporting a vertical pile of work-pieces on said guide member; a pusher block positioned to push the lowermost work-piece from said pile and from said guide member so that it may fall by gravity to said work rest; a pneumatic cylinder; a piston in said cylinder; a piston rod extending from said piston to an operative connection with said pusher

block to actuate the latter; a two-way valve for alternately connecting the opposite ends of said cylinder with a source of fluid pressure; a cam shaft; a motor rotating said cam shaft; a first cam in said shaft; means operable by said first cam for moving said feed wheel toward and away from said grinding wheel; a second cam on said cam shaft; and means for actuating said valve from said second cam so that the changes in flow of said fluid pressure will be in synchronism with the movements of said feed wheel.

3. A work-piece feeding and ejecting attachment for centerless grinding machines, of the type having a grinding wheel, a feed wheel and a work rest positioned between said wheels, comprising: pneumatically operated feeding means for placing a work piece on said work rest; a motor operated device for moving said feed wheel toward and away from said grinding wheel; a valve controlling said pneumatically operated means; means for operating said valve from said motor operated device so that the movements of said valve will be synchronized with the movements of said feed wheel; a pneumatically operated ejecting means positioned on the opposite side of the work rest from the pneumatically operated feeding means and in alignment with a work-piece resting on said rest; and pneumatic conduits connecting said pneumatically operated ejecting means with said valve so that the latter will control the ejection of the finished work pieces from said work rest.

JOHN E. HECKETHORN.
